UNITED STATES PATENT OFFICE.

HORACE B. MURDOCK, OF DETROIT, MICHIGAN, ASSIGNOR TO JAMES JENKS, OF SAME PLACE.

INJECTOR.

SPECIFICATION forming part of Letters Patent No. 259,649, dated June 13, 1882.

Application filed October 12, 1881. (No model.)

To all whom it may concern:

Be it known that I, HORACE B. MURDOCK, of the city of Detroit, in the county of Wayne and State of Michigan, have invented an Improvement in Injectors, of which the following is a specification.

The nature of this invention relates to certain new and useful improvements in injectors, by means of which the hollow plugs which form the steam-jet and combining tubes in said injectors can be easily seated or withdrawn when necessary for cleaning or repairs, and without the use of a special tool, through the steam or water connections.

The invention consists in the peculiar and novel construction of such tubes or plugs and their combination with an injector, as more fully hereinafter set forth.

Figure 1 is a vertical central section of an injector such as was patented to James Jenks, October 19, 1880, the patent being No. 233,418. Fig. 2 shows details enlarged and in perspective.

In the accompanying drawings, which form a part of this specification, A represents the steam-inlet connections of an injector.

B is the steam-plug, forming a communication through which the steam passes to the combining-tube C. The plug B is cast with a recess, N, as shown in Fig. 2, such recess being divided by the partitions a, cast therein.

The combining-tube C is cast with a seat, b,

below which the tube is threaded, as shown, and the upper face of the seat-ring b is cast either with a recess similarly divided, as described in connection with the plug B, or has flanges c, at equal distances apart, as shown in the enlarged figure, the latter being the reverse of the former.

The part of the injector into which the plug B is inserted is made sufficiently large to allow the plug C to be first carried through such opening and screwed to its seat, after which the plug B is inserted and screwed to place. A tool, D, being simply a piece of gas-pipe of suitable size, with notches d cut at equal distances apart in its lower end, engages with the partitions a or with the flanges c, and, passing through the connection A, enables the operator to easily remove and replace the plugs when necessary without difficulty.

What I claim as my invention is—

1. In an injector, the screw-plug B, provided with a central nozzle, and cast with a recess, N, having dividing-partitions a, substantially as shown and for the purpose specified.

2. In an injector, the plug C, provided with a central nozzle, and cast with a seating-flange, b, and projections c thereon, substantially as shown and for the purpose specified.

HORACE B. MURDOCK.
